(57) **CLAIM**

The ornamental design for a faucet bracket, as shown and described.

DESCRIPTION

FIG. 1 is a perspective view taken from the top, front, and right side of a faucet bracket showing my new design;

FIG. 2 is a top plan view of the faucet bracket shown in FIG. 1;

FIG. 3 is a bottom view of the faucet bracket shown in FIG. 1; FIG. 4 is a front elevational view of the faucet bracket shown in FIG. 1;

FIG. 5 is a rear elevational view of the faucet bracket shown in FIG. 1;

FIG. 6 is a left elevational side view of the faucet bracket shown in FIG. 1; and,

FIG. 7 is a right elevational side view of the faucet bracket shown in FIG. 1.

The broken lines are for illustration purposes only and form no part of the claimed design.
